SUPPORT FOR TUBES OR THE LIKE AND METHOD OF MANUFACTURE THEREOF

Vernon D. Goodwin, Emporium, Pa., assignor to Hygrade Sylvania Corporation, Salem, Mass., a corporation of Massachusetts

Application March 26, 1935, Serial No. 13,058

9 Claims. (Cl. 250—27.5)

This invention relates to support members, such for example as are employed in lamps, tubes or the like, and more particularly to a method of forming such supports.

5 An object of the invention is to provide an improved method for forming an insulator body, for example a ceramic block with perforations extending at an angle to each other through the block.

10 In certain types of devices for example present day radio tubes or the like, it is customary to support or space the electrodes or other parts, by means of an insulator member of insulating material. However, these supports are usually designed with as small a mass as possible consistent with the necessary mechanical rigidity for supporting or spacing the tube parts, and in many cases these supports are of such small size as to render the provision of perforations therethrough by ordinary drilling impracticable.

15 Accordingly, it is a principal object of this invention to provide an improved method of forming an insulating block with transverse perforations.

20 Another object of the invention is to provide an improved method of molding a body with perforations extending therethrough and at an angle to each other.

25 A feature of the invention relates to an improved method of providing a body with a transverse perforation by employing a set of punches or forming tools moving substantially parallel to each other.

30 Another feature relates to an improved method of forming a ceramic or similar body with two or more perforations extending at right angles to each other, by employing punches which move in the same general direction.

35 Another feature relates to an improved method of providing a body with a non-linear perforation therethrough.

40 A further feature relates to an improved form of supporting and/or spacing member for lamps, tubes and the like.

45 Other features and advantages of the invention not specifically enumerated will be apparent after a consideration of the following detailed description and the appended claims.

50 While the invention will be disclosed herein as embodied in one particular form of body or spacer member, it will be understood that this is done merely for explanatory purposes and not by way of limitation. Furthermore, while the invention will be described in connection with the formation of a ceramic or similar member, it is equally

well applicable to the formation of any body which is required to be perforated in mutually perpendicular directions without using a drilling operation and without using dies or punches moving in different planes.

5 Accordingly, in the drawing Fig. 1 is a perspective view, partly sectional, illustrating a typical block embodying features of the invention.

10 Fig. 2 is an explanatory diagram schematically illustrating how certain of the perforations shown in Fig. 1 are formed.

15 Fig. 3 is a typical form of radio tube embodying a spacer such as shown in Fig. 1.

20 Fig. 4 is a partial sectional view of Fig. 3 taken along the lines 4—4 thereof.

25 Referring more particularly to Fig. 1, the numeral 1 represents a block of material for example ceramic material, lavite or the like, such as is ordinarily employed in radio tubes, lamps, etc. Such a block is generally employed for the purpose of spacing the several electrodes from one another, and also as an anchor for other electrodes.

30 As is well-known the electrodes of radio tubes are usually formed with uprights or side-rods, which are adapted to enter corresponding perforations in the block 1. Thus in Fig. 1 the perforations 2, 3, are adapted to receive the upper ends of the plate support side-rods 4, 5, while the perforations 6, 7, are adapted to receive the upper ends of the grid support side-rods (see Fig. 30).

35 Preferably, although not necessarily, the perforations 2, 3 and 6 are of the same shape in cross section as the cross section of the respective side-rods. If desired the perforation 7 may be elongated in cross section allowing the 35

grid to expand and contract at different temperatures. The perforations 8 and 9 may be for the purpose of receiving tension springs for the filament, and preferably each of these latter perforations is provided with a shoulder 10 against 40

which a respective spring 11 seats. Each spring may have fastened thereto a hook 12 to engage the bight of the usual inverted V-filament, the springs and hooks serving to maintain the filament taut.

45 It will be understood of course that the lower ends of the filament as well as the lower ends of the various electrode side-rods, are supported from the usual reentrant press (not shown). Any well known manner of fastening the block 1 to the side-rods may be employed, for example the plate side-rods 4, 5 may be swaged above and below the block to prevent the said block moving vertically on the side-rods.

50 In order to support the electrode assembly including the block 1, against horizontal or tilt-

ing movement with respect to the tube wall 13, the said block is preferably provided with free-ended metal springs 14, 15, the free ends of these springs preferably being bent as indicated 5 to provide an elastic support against the inner wall of tube 13 as indicated in Fig. 4 of the drawing.

It will be noted that the perforations 2, 3, 6, 7, 8 and 9 in block 1 have their axes extending in 10 the same direction through the block so that these perforations may be formed by a suitable die, punch or forming tool, moving for example in a vertical plane with respect to the block. However since the springs 14 and 15 must extend transversely through the block, it becomes 15 necessary to provide the block with corresponding perforations to receive these springs.

In accordance with this invention the perforations to receive the spring supports 14 and 15 20 are preferably formed by a punching or die operation at the same time that the perforations 2, 3, 6, 7, 8 and 9 are formed. It is desirable for various reasons however to be able to form the spring receiving perforations at the same 25 time, or at least by a punch or die moving in substantially the same plane as the punches forming the remaining perforations. One manner of accomplishing this result is diagrammatically illustrated in Fig. 2. In this figure the 30 block 1 is held in a suitable retaining member and sets of punches or forming tools 16, 17 and 18 are provided. One of these sets of punches is adapted to form the transverse perforation at one end of the block for receiving spring 14, while 35 a similar set of punches is adapted to form the transverse perforation at the opposite end of the block to receive spring 15. Punches 16 and 17 are preferably movable vertically as a unit so that in moving they form corresponding notches 19, 20 in the under-face and side faces of block 1. Likewise as punch 18 moves downwardly in 40 a vertical direction and in the same plane as the punches 16 and 17, it forms a window or recess 21. As indicated in Fig. 2 the punches 16, 17 and 18 are designed to overlap in their 45 movement so that the window 21 communicates with the notches 19 and 20, thus providing a transverse passageway for the spring member 14. Preferably the face of punch 18 has the shape 50 shown in Fig. 2 so that the spring support 14 may be locked in position thus restraining it against sliding movement with respect to the block.

It will be understood of course that the punches 55 16, 17 and 18 may be operated together, or if desired the punches 16 and 17 may first form the notched sections 19 and 20 and then the punch 18 may be operated to form the window 21. In any event the punches 16, 17 and 18 60 all move in the same general direction as the punches that form the perforations 2, 3, 6, 7, 8 and 9.

It will be understood of course that the formation of the several perforations may be 65 achieved when the block 1 is in a somewhat softened state and the perforating may be affected while the block is being molded to the shape shown. It will also be understood that instead of using punches to form the different 70 perforations, a bi-part mold may be employed having projections corresponding to the members 16, 17 and 18 so that as the block 1 is being molded the said projections act on the block in substantially the same manner as when 75 punches are employed as described above.

The wire 14 may be previously formed with the bowed portion 22, or if desired the said wire may be substantially straight and after being inserted through the block a die having a face similar to the face 23 of punch 18 may be employed to off-set the central portion of the wire 14 thus locking it against sliding movement in the block 1.

From the foregoing it will be seen that there is provided a method of forming a body with such 10 as an insulator block with perforations extending therethrough in mutually perpendicular directions, and the punch or molding members for producing these perforations may move in the same general plane. However, various changes 15 and modifications may be made herein without departing from the spirit and scope of the invention thus for example the punches 16, 17 and 18 instead of moving perpendicular to the face of the block 1 may move at an angle so that the 20 transverse perforation resulting from the movement of the punches 16, 17 and 18 may extend at any desired angle with relation to the perforations 2, 3, 6, 7, 8 and 9. Likewise instead of providing the recess 21 in the upper face of the 25 block and notching the lower face as at 19, 20, the latter notches may be provided in the upper face and the recess 21 may be formed in the lower face. It will be understood therefore that the terms "top" and "side" or "lateral" as employed 30 in the claims is merely relative, and the invention is not limited to the formation of the passages laterally through the block as distinguished from passages extending from top to bottom of the block.

The method of forming as described, is particularly well suited to the making of insulator members of moldable ceramic materials. Thus the ceramic materials in powdered form may be mixed with a suitable binder and baked to a 40 suitable temperature to bond the particles. The semi-plastic mass may then be inserted in a suitable mold to form the various passages as described and also to shape the block as a whole. The molded perforated block may then be fired 45 and if desired suitable reaming or boring tools may be used to enlarge the passages or smooth any irregularities in their inner surfaces. Alternatively the ceramic block may first be molded with some of the passages, and the remaining 50 passages formed after removal from the mold but preferably prior to firing.

What I claim is:

1. A spacer member for radio tubes comprising a block having opposite faces notched, and having a third face provided with a recess, the recess communicating with the notches to form a transverse passage through the block.
2. A support member for radio tubes comprising a block having aligned notches in the lateral walls thereof and a recess in the top wall thereof, said recess and notches overlapping to define a passageway extending transversely through the said member.
3. A spacer member for radio tubes comprising a block of insulating material having a set of perforations extending therethrough from top to bottom, and another passageway extending laterally therethrough, the said passageway being defined by a recess on the top face of said block and aligned notches in the lateral walls of said block, said notches and recess communicating with each other.
4. A support block of the character described having a plurality of passages extending there- 75

5 through in a vertical direction and a plurality of passages extending therethrough in a horizontal direction, each of the latter passages being defined by lateral notches and a window in the top face of said block communicating with said notches.

10 5. A spacer member for radio tubes comprising a block of insulating material having a transverse passage therethrough defined by lateral notches and a top recess, and a free-ended spring wire positioned in said passage and having the free ends extending beyond said block.

15 6. A spacer member according to claim 5 in which the free ends of the spring are bent.

7. A spacer member according to claim 5 in which the spring wire has a portion of its length where it passes through said block off-set, and

said passage is also provided with a corresponding surface to receive said off-set portion of said wire.

8. A spacer member for a radio tube comprising a block of insulation, and a spring wire passing transversely through said block with its free ends extending outwardly from said block, said wire having an off-set portion in its length where it passes through said block.

9. A spacer and support member for radio tubes 10 comprising a block of insulating material having a transverse passage therethrough, a spring wire passing in said passage having its free ends extending beyond said block, said block and wire having means to prevent said wire sliding in said 15 block.
